(57) **CLAIM**

The ornamental design for a work station, as shown and described.

DESCRIPTION

FIG. 1 is an oblique view of one embodiment of the invention illustrating rotatable extensions at each end of the central work surface;

FIG. 2 is a front elevation view of the invention shown in FIG. 1;

FIG. 3 is a back elevation view of the invention shown in FIG. 1;

FIG. 4 is a side elevation view of the invention shown in FIG. 1;

FIG. 5 is an opposite side elevation view of the invention shown in FIG. 1;

FIG. 6 is a top view of the invention shown in FIG. 1;

FIG. 7 is a bottom view of the invention shown in FIG. 1;

FIG. 8 is an oblique view of the invention shown in FIG. 1 illustrating a fully rotated position of one extension of the work surface, the extension able to assume an angular position of rotation between that shown in FIG. 1 and FIG. 8;

FIG. 9 is a front view of the invention shown in FIG. 8;

FIG. 10 is a back elevation view of the invention shown in FIG. 8;

FIG. 11 is a side elevation view of the invention shown in FIG. 8;

FIG. 12 is an opposite side view of the invention shown in FIG. 8;

FIG. 13 is a top elevation view of the invention shown in FIG. 8;

FIG. 14 is a bottom view of the invention shown in FIG. 8;

FIG. 15 is an oblique view of the invention shown in FIG. 1 illustrating a fully rotated position of the opposite extension of the work surface, the extension able to assume an angular position of rotation between that shown in FIG. 1 and FIG. 15;

FIG. 16 is a front view of the invention shown in FIG. 15;

FIG. 17 is a back elevation view of the invention shown in FIG. 15;

FIG. 18 is a side elevation view of the invention shown in FIG. 15;

FIG. 19 is an opposite side view of the invention shown in FIG. 15;

FIG. 20 is a top elevation view of the invention shown in FIG. 15; and,

FIG. 21 is a bottom view of the invention shown in FIG. 15.
